(57) **CLAIM**

The ornamental design for a framing stud, as shown and described.

DESCRIPTION

FIG. 1 is a top perspective view of a first embodiment of a framing stud, showing my new design.

FIG. 2 is a bottom perspective view thereof.

FIG. 3 is a top plan view thereof.

FIG. 4 is a bottom plan view thereof.

FIG. 5 is a left side elevation view thereof.

FIG. 6 is a right side elevation view thereof.

FIG. 7 is a front elevation view thereof.

FIG. 8 is a rear elevation view thereof.

FIG. 9 is a top perspective view of a second embodiment of a framing stud, showing my new design.

FIG. 10 is a bottom perspective view thereof.

FIG. 11 is a top plan view thereof.

FIG. 12 is a bottom plan view thereof.

FIG. 13 is a left side elevation view thereof.

FIG. 14 is a right side elevation view thereof.

FIG. 15 is a front elevation view thereof; and,

FIG. 16 is a rear elevation view thereof.

The dash-dot-dash broken lines in the drawings illustrate portions of the framing stud that form no part of the claimed design.

1 Claim, 8 Drawing Sheets
